UNITED STATES PATENT OFFICE.

EDWARD J. BRENNAN, OF OAKVILLE, CONNECTICUT.

INSIDE COVER FOR SMOKING-TOBACCO BOXES.

1,280,383.

Specification of Letters Patent.

Patented Oct. 1, 1918.

Application filed February 5, 1917, Serial No. 146,571. Renewed February 13, 1918. Serial No. 216,975.

To all whom it may concern:

Be it known that I, EDWARD J. BRENNAN, a citizen of the United States, residing at Oakville, county of Litchfield, State of Connecticut, have invented an Improvement in Inside Covers for Smoking-Tobacco Boxes, of which the following is a specification.

This invention relates generally to supplemental dispensing tops or lids for containers, with more particular reference to a particular type of sheet-metal container in which pipe and cigarette tobacco is now extensively packaged and sold. A popular style of tobacco package now in general use is that of a comparatively thin tin box having flat front and rear faces, rounded narrower sides, a flat bottom and a hinged top, this particular shape having been found for a certain desired and convenient size to be best adapted for use as a dispensing container in view of the fact that it may be carried in the pocket of a garment without excessive bulging.

In filling a pipe or rolling a cigarette, the packed tobacco is loosened or somewhat granulated with the finger or with a pencil or the like, and then generally poured from the container into the pipe or upon the cigarette paper. When the tobacco has become somewhat dry and attempt is made to fill a pipe or roll a cigarette out of doors, the fact that the whole end of the can must be opened oftentimes occasions excessive wasting of the tobacco, particularly on a windy day, as it is likely to flow too freely from the can and much thereof lost by being blown away or an over-supply accidentally dispensed or spilled and thus lost or wasted. The principal object of the present invention is the provision of a supplemental lid or top, which may be easily and quickly applied to the box in such manner as not to interfere with operation of the permanent cap or cover which reduces the area of the mouth of the box to such comparatively small size that the amount of tobacco which can be caused to flow therethrough is under more nearly perfect control, and in which all of the tobacco except that which is flowing through the small dispensing orifice is protected from the elements and more or less safeguarded against loss through any ordinary accident.

My invention will be readily understood by reference to the accompanying drawing, forming a part of this specification, in which—

Figure 1 is a perspective view of a tobacco box of the type to which I have referred, with the hinged cover in open position, to which has been applied a supplemental dispensing lid embodying my invention; 60

Fig. 2 is a substantially central transverse section of the top portion of the same;

Fig. 3 is a perspective view of the supplemental lid showing one side edge thereof, 65 and

Fig. 4 is a similar view showing the other side edge thereof.

Referring now to the drawings in detail, numeral 7 designates a well-known type of dispensing container for tobacco, the same being laterally flattened with the narrower sides 8 and 9 rounded, to give the can a form which adapts it to be more conveniently carried in the pocket. The telescoping top or 70 cover 10 is hinged to the rear wall 11 of the can, and for purposes of economy in manufacture the hinge-pin 12 is secured to this wall by notching the upper edge thereof and 75 curling the lips 13 thus formed around said pin, the rear wall of the cover being provided with a projecting extension which is similarly notched to form lips which alternate with the lips 13 and are curled around said pin. Obviously, such construction necessitates the provision of a comparatively 80 wide recess in the upper edge of the rear wall of the can.

My supplemental lid comprises a thin flat plate 14, the width of which is the same as the width of the mouth of the can and which in length is somewhat less than the length of said mouth. One end 15 of this plate is rounded to conform to the rounded side 8 of the can, and it will therefore be seen that 85 this lid will snugly fit within the mouth of the can, as shown in Fig. 1, a notch 16 being preferably provided in the rounded end of the plate to receive a double seam 17 which forms an interior protuberance—cans of 90 this type being almost invariably formed with this seam which is located at the middle of one of the narrower sides thereof. 95

These cans are furthermore invariably provided with a groove or bead 18 near the 100 upper end thereof to give greater strength and rigidity to the metal at this comparatively weaker part of the body and prevent distortion thereof. The presence of this groove enables me to provide simple means 105 for removably applying my supplemental lid or top to the can. For this purpose, I 110

provide on one side edge of the plate 14 the depending tongues 19 and 20, the lower ends 21 and 22 of which are outwardly flanged. The length of each tongue is the same as the 5 distance from the top edge of the can to the groove 18, and the length of each of the flanges approximates the depth of said groove. At the other side edge of the plate I provide the elongated depending lip 23 and 10 the outwardly flanged tongues 24 and 25, corresponding to the tongues 21 and 22, at the ends thereof.

It will now be seen that by slightly spreading apart the flat side walls of the 15 can, which can readily be done within the limits of elasticity of the metal by pressing the rounded sides toward each other, the plate 14 may be passed into the mouth of the can so that the flanges of the tongues 21, 22, 20 24 and 25 enter the groove 18, thus firmly holding the lid in place with the top face thereof flush with the upper edge of the can body, the notch 16 receiving the protruding seam 17 and the lip 23 covering the opening 25 which would otherwise be caused by the recess in the top edge of the rear wall of the can, to which I have referred. Therefore, when the box is opened by throwing back the hinged cover 10, the mouth thereof still 30 remains almost completely closed, the comparatively small orifice 26 at the end of the lid 11 being the only opening through which the contents of the box may be dispensed.

I have shown the end 27 of the plate 14 35 cut in concave form. This enables me to provide a substantially circular dispensing orifice which is of pleasing appearance and possibly more satisfactory in dispensing the contents of the can. The shape of this end, 40 however, is of minor importance. The lid might possibly be more cheaply constructed and just as satisfactorily answer all purposes by cutting it with a square end opposite the rounded end.

45 With respect to my improved supplemental dispensing lid, it will be noted that its application to the box does not interfere in any way with the operation of the usual hinged cover; that it may be applied to the 50 box and removed therefrom with the utmost ease, wherefore it may readily be taken from an empty box and applied to a fresh box as occasion requires; that it serves to supplement the groove 18 in strengthening the top 55 of the box; that the orifice is large enough

to permit of comparatively free flow of the tobacco therethrough, or for the insertion of a pencil or like article for the purpose of "loosening" the packed tobacco, and that it not only enables the user to better control 60 the amount of tobacco dispensed from the can and prevents waste by blowing away of the tobacco when used in the open air on a windy day, but it also minimizes the loss of tobacco which generally follows the accidental dropping of the can while being used. Furthermore, not the slightest change is 65 required in present methods of manufacturing the cans and packing the tobacco therein—the latter being generally first wrapped 70 in moisture-proof paper—and that the top portion of the paper wrapper may be torn off in the usual manner, to render the tobacco accessible, before applying the improved dispensing lid.

75 I claim as new and desire to secure by Letters Patent:

1. An inside cover for boxes of the character described, comprising a flat plate corresponding in form to the shape of the 80 mouth of the box, and cut away at one end for the purpose set forth, both sides of said plate being provided with depending tongues outwardly flanged to adapt them to engage the groove near the top of the box to 85 detachably retain the plate in place, and one side of said plate being provided between the tongues with a depending lip adapted to cover the opening at the top of the box caused by displacement of metal to form the 90 hinge.

2. An inside cover for boxes of the character described, comprising a flat plate corresponding in form to the shape of the 95 mouth of the box, said plate being cut away at one end to provide a dispensing orifice and provided at the other end with a notch to receive the seam of the box, both sides of said plate being provided with depending tongues outwardly flanged to adapt them to 100 engage the groove near the top of the box to detachably retain the plate in place, and one side of said plate being provided between the tongues with a depending lip adapted to cover the opening at the top of the box 105 caused by displacement of metal to form the hinge.

In testimony whereof I affix my signature.

EDWARD J. BRENNAN.
